METHOD OF MANUFACTURING NONINDUCTIVE HELICAL FILAMENTS

Application filed January 28, 1930. Serial No. 423,933.

This invention relates to electron discharge devices and particularly relates to electron discharge devices employing hot cathodes of the indirectly heated type and more particularly relates to the heater element of said cathode.

This application is a continuation in part application of my copending application Serial No. 402,559 filed October 26, 1929, entitled "Method of manufacturing electron discharge devices".

One of the objects of the present invention is to provide a method of forming a non-inductive twin coil helical filament.

15 Another object of this invention is to provide a method for producing a non-inductive heater element for an indirectly heated cathode.

Other objects and advantages will become 20 apparent as the invention is more fully disclosed.

In copending application Serial No. 402,559 above identified, are disclosed two types of electron discharge devices employing 25 electron emitting cathodes of the indirectly heated type, which are known to the trade as the 227 and the 224 radio receiving tubes. In each of these tubes it is highly essential for best results to employ a heater 30 element in the cathode electrode which is substantially non-inductive.

A suitable type of non-inductive heater element is also disclosed therein which is comprised substantially of a refractory 35 metal filament shaped in the form of a double helix the turns of each of said helices lying substantially in the same circumferential plane and in respective parallel spaced relationship.

40 As disclosed in said copending application the specific type of double helix set forth therein may be formed from a hairpin shaped filament of the desired or predetermined wire size, length and diameter to conform with 45 the specifically desired electrical and physical operating characteristics. The loop portion of the hairpin is engaged in a slot in the end of a mandrel of the desired coil inside diameter and the two legs of the filament 50 wound about the mandrel the desired number

of turns in the desired parallel spaced relationship. The specific pitch to the turns and number of turns per inch depends upon the particular type cathode sleeve member within which it is to be incorporated. In the 55 winding of the coil the two legs of the filament are preferably maintained in relatively close parallel spaced relationship to each other while maintaining each set of two wire turns at a relatively larger parallel spacing. 60 This arrangement effectively gives almost a complete neutralization of the electrical fields about the wire and coil and produces a coil which has a relatively low "hum" characteristic due to such electric fields when 65 employed in a thermionic discharge device.

In the forming of such a type coil mechanically and in relatively large numbers it has been found exceedingly difficult to effect a relatively close parallel spacing of the two 70 legs of the filament while maintaining at the same time a relatively greater parallel spacing of each pair of the closer spaced turns. This may be effected by the present invention.

Before further disclosing the nature of the 75 present invention reference should be had to the accompanying drawing wherein;

Fig. 1 is a side elevational view of a simple device for forming the specific non-inductive coil type heater element of the present 80 invention;

Fig. 2 is a top view looking down on the device;

Fig. 3 is a view taken along plane III-III 85 in Fig. 1;

Fig. 4 is a side elevational view of the device shown in Fig. 1;

Fig. 5 is an enlarged sectional view taken along plane V-V in Fig. 1;

Fig. 6 is an enlarged sectional view taken 90 along plane VI-VI in Fig. 1;

Fig. 7 is an enlarged view of the tip of the mandrel about which the coil type filament is wound;

Fig. 8 is a reverse view of the same;

Fig. 9 is an enlarged view of hairpin type filament; and

Fig. 10 is an enlarged view of the complete non-inductive coil type heater element.

Referring to Fig. 1 the device for winding 100

the non-inductive coil type filament illustrated in Fig. 10, is comprised substantially of a cross head 1, supporting posts 2 and 3, a guide plate 4, a screw driving element 5 which may be turned by means of thumb plate 6 in the end of which screw driving element is inserted a mandrel 7.

Guide plate 4 is provided with a suitable opening 8 to receive mandrel 7 and is also provided with openings 9 and 10 on opposite sides of the mandrel opening 8, to receive the legs 11 and 12 of the hairpin filament shown in Fig. 9. The relative spacing of openings 8, 9 and 10 being in accordance with the desired spacing of the convolutions of the finished coil.

The mandrel 7 is comprised substantially of a wire having the desired diameter, strength and rigidity, such as for example a molybdenum wire, the tip end of which is grooved in accordance with the design indicated in Figs. 7 and 8, for the purpose of engaging the loop end 13 of the hairpin filament shown in Fig. 9, thus restraining the loop end of the filament from lateral displacement when the mandrel is revolved about its longitudinal axis.

A coil type heater element formed in accordance with the present invention is comprised substantially of twin helices lying in the same cylindrical plane, the respective turns of said helices being in substantial parallel spaced relationship.

From an examination of the enlarged view shown in Fig. 10 it may be noted that the turns of the filament are substantially in spaced pairs and that each of the spaced twin turns belong to opposite helices. This feature is highly desirable for the purposes of the present invention, in that it provides for a substantial neutralization of the electric field in each wire due to the passage of an alternating electric current therethrough. This neutralization of electric fields within the heater element eliminates a source of undesirable electric discharges resulting in deleterious "hum" characteristics of a thermionic discharge device employing an indirectly heated cathode.

The method of obtaining mechanically this twin turn spacing of a helical coil is one of the features of the present invention. It may be noted in Fig. 1 that guide plate 4 has a cut away section 14 adjacent to mandrel opening 8.

In Fig. 2 it may be noted that one of the openings 9 and 10 through which extend filament legs 11 and 12 of the hairpin filament, lies within this recessed portion. I have found that when mandrel 7 is revolved about its longitudinal axis the two legs of a hairpin filament, the apex of which is engaged in the end of the mandrel 7, tend to wind or arrange themselves in the form of twin helices about the mandrel, the individual

turns being in substantially parallel spaced relationship. Such a coil does not give the maximum in electric field neutralization for the purpose of the present invention.

I have found that this maximum effect may be obtained by winding the coil so that the two legs of the filament arranged themselves in the twin turn spaced relationship shown herein. I obtain this twin turn parallel spacing of the double helix by providing means comprising shoulder 15 in guide plate 4 for guiding one leg of the filament in closer spaced relationship to the other free winding leg, than would normally be obtained.

This mechanical feature of the invention is more clearly set forth in Figs. 5 and 6 which show in enlarged cross sectional view the manner in which the shoulder 15 effects the spacing of the coil convolutions. Ordinarily, as above noted, when mandrel 7 is rotated about its longitudinal axis the legs 11 and 12 of a hairpin filament, the apex of which is engaged in groove 16 in the end of the mandrel, would tend to adjust themselves in parallel convolutions about the mandrel, the spacing and the number of turns per inch being dependent upon the spaced relationship of the openings 9 and 10 to the mandrel and the number of turns per inch to the thread of the screw driving element 5. This condition would hold true as long as the openings 8, 9 and 10 in guide plate 4 lie in substantially the same horizontal plane.

By lowering the plane of one of the openings as by recessing the grid plate member in the manner shown in Figs. 1 and 2 the parallel spacing of the twin turns is changed and shoulder 15 then becomes a guiding member for spacing one of the convolutions of the coil to the other. This can be clearly seen in Figs. 5 and 6 of the attached drawing wherein in the convolutions formed by filament leg 12, which for the purpose of the present invention may be denoted as the free or unengaged convolution, is shown in position within the guided convolution 11, the drawing setting forth clearly how shoulder 15 serves to guide the convolutions into the desired spaced relationship. The height of the shoulder 15 and the distance from the mandrel being controlling factors. In Fig. 6 the reverse view is shown.

As a result of the practice of the present invention I am enabled to mechanically form a double helix coil, the terminals thereof extending from one end, and the convolutions lying substantially in the same circumferential plane, and in relative parallel spaced relationship with each other, and am also enabled to arrange the respective convolutions of one of said helices in predetermined or desired close spaced relationship with the convolutions of the other helix.

Such a type coil is useful in the art as an electrically non-inductive coil, and may be

- particularly employed as a heater element in thermionically active hot cathodes of the indirectly heated type wherein it is specifically desired to eliminate deleterious electrical discharges caused by induced electrical currents in such a heater element when energized by the passage of an alternating current therethrough.
- In accordance with this specific application of the present invention the double helix element is comprised of a tungsten filament of approximately 6.5 mil diameter, preferably of the non-sag type. At this diameter the length requisite to give a current consuming capacity or resistance at the required 2.5 volts operating voltage of a common type radio receiving tube known to the trade as 227 or 224 tubes, is about 23 millimeters. This length of filament is wound upon a mandrel of about 25 mil diameter, adjusting the spacing of the turns to give approximately 20 double turns or 40 single turns per inch. This spacing provides a heater element with this length filament having approximately 10 twin turns or 20 single turns each of the twin turns being spaced apart about 1 millimeter distance and each of the sets of twin turns about twice this distance. By proper adjustment of the filament diameter, length, mandrel size, and pitch of the coil convolutions, heater coils of any desired dimension and electrical characteristics may readily be obtained.
- The coil thus prepared may be employed in accordance with the invention set forth in the parent application of the present invention above identified.
- Having broadly and specifically set forth the nature and scope of the present invention it is apparent that there may be many modifications in the apparatus and method of forming the specific type of non-inductive coil type filament herein disclosed, but such modifications and variations are contemplated as may fall within the scope of the following claims:—
- What is claimed is:
1. The method of forming a twin helical filament which comprises winding the legs of a hairpin filament in parallel spaced relationship about a mandrel of the desired diameter.
  2. The method of forming a twin helical filament which comprises shaping a length of the filament in the form of a hairpin, engaging the loop of the hairpin in the end of a mandrel of the desired diameter, and winding the two legs of the filament about the mandrel in the desired parallel spaced relationship.
  3. The method of forming a double helical filament, the convolutions thereof lying in substantially the same axial plane and in parallel spaced relationship, which comprises engaging the loop end of a hairpin filament in the end of a mandrel of the desired diameter, and winding the two legs of the filament about the mandrel in the desired spaced relationship.
4. The method of forming a double helical coil the convolutions thereof lying in substantially the same plane and in parallel spaced relationship, which comprises supporting a pair of wires on opposite sides of a mandrel, and winding said wires in parallel spaced relationship about said mandrel.
5. The method of forming a non-inductive double helical filament the convolutions thereof lying in substantially the same plane and in parallel spaced relationship which comprises supporting a pair of wires on opposite sides of a mandrel, winding said wires about said mandrel in parallel spaced relationship, and guiding one of said wires in relative close relationship to the other.
6. The method of forming a non-inductive coil type filament which comprises shaping the filament into a hairpin, and winding the two legs of said hairpin about a mandrel in relative close spaced relationship maintaining a relatively greater spaced relationship between the twin convolutions.
7. The method of forming a non-inductive coil type filament which comprises engaging the apex of a hairpin filament in the end of a mandrel, winding the legs of said hairpin about the mandrel in parallel spaced relationship, guiding one of said legs in relative close spaced relationship to the other.
- In testimony whereof, I have hereunto subscribed my name this 24th day of January, 1930.
